UNITED STATES PATENT OFFICE.

JOHN B. MITCHELL, OF PORTLAND, MAINE, ASSIGNOR OF ONE-HALF TO
WILLIAM H. STEVENS, OF SAME PLACE.

PENCIL-SHARPENER.

SPECIFICATION forming part of Letters Patent No. 642,914, dated February 6, 1900.

Application filed October 5, 1899. Serial No. 732,595. (No model.)

To all whom it may concern:

Be it known that I, JOHN B. MITCHELL, a citizen of the United States, residing at Portland, in the county of Cumberland and State of Maine, have invented certain new and useful Improvements in Pencil-Sharpener; and I do hereby declare the following to be a full, clear, and exact description of the invention, such as will enable others skilled in the art to 10 which it appertains to make and use the same.

My invention relates to improvements in pencil - sharpeners. It is designed to sharpen pencils and to form a perfect point at the end.

15 In the drawings herewith accompanying and making a part of this application, Figure 1 is a perspective view of my improved sharpener. Fig. 2 is a longitudinal sectional view taken lengthwise through the slots, the sharpener being in the position that it is when the sharpening process is completed. Fig. 3 is a similar view showing the sharpener pushed back upon the pencil, a convenient position when not in use. Figs. 4, 5, and 6 are detail 20 views showing some of the different forms which the cutting edge of the slots may assume; and Fig. 7 is a transverse sectional view of a pencil with sharpener in position, taken on line X X of Fig. 2.

30 The same letters of reference refer to like parts.

In said drawings, A represents a holder which may vary in form, adapted to receive the end of the pencil. Extending out longitudinally from said holder are similar spring-blades B, having slots C extending longitudinally therein, said slots having one or both of their edges sharpened to form the working edges of the sharpener. The blades are 35 brought closely together at the ends, as seen in Figs. 1 and 2, the curvatures of the blades being such that the outer apexes of the slots come together, as shown in Fig. 2, the extremes of the blades extending beyond the 40 ends of the slots. These blades have normally yielding contact at their free ends. The cutting edges may have any desirable configuration. Among many that might be used I have illustrated three—in Fig. 4 a plain bevel, 45 in Fig. 5 a saw-tooth edge, and in Fig. 6 a corrugated edge; but I do not wish to limit

myself to the use of any particular configuration of the cutting edge. The slots are tapered toward their outer extremities. If both edges of the slots are sharpened, the pencil 55 will be sharpened whichever way it is turned in the sharpener. If only one edge in each slot is sharpened and the sharpened edges are at opposite sides, the pencil will be sharpened only when turned in one direction. I 60 do not limit myself to the sharpening of all the edges of the slots. When the slots are substantially elliptical in form, the cutting of the taper in the wood of the pencil will be facilitated, the slots can be more readily cut 65 in the blades, and the slots in the blades would not have to be so wide as would be necessary if they diverged throughout their whole extent.

The operation of my improved pencil-sharpener is as follows: The end of the pencil, which is preferably rendered somewhat tapering before the pencil-sharpener is applied, is inserted through the holder and forced forward until the point of the pencil comes with 70 in the range of the cutting edges of the slots. The pencil is then rotated until the end is sufficiently sharpened. To form the point on the end of the lead, the pencil is gradually pressed forward until the point of the pencil 75 reaches the apex of the slots. The pencil being turned in the sharpener forms a perfect point on the end of the pencil, the pitch of which will be determined by the angle formed by the separation of the two blades from the 80 apex of the slots rearwardly toward the holder. When the pencil is sharpened, the sharpener may be removed entirely from the pencil, or it may be forced toward the opposite end until the point of the pencil projects somewhat 85 beyond the ends of the blades, as seen in Fig. 3, where it may remain until the pencil needs resharpening or repointing, or it may, if desired, be removed and placed on the other end of the pencil. 95

The advantages of my improved pencil-sharpener are that the point is formed while being held throughout its entire length on opposite sides between yielding jaws or blades, a portion of the lead projecting between the 100 sides of the slot, and thus preventing any strain which would tend in any way to break

the lead. It is convenient to use and simply and cheaply constructed. It can be carried on the pencil in a position to be readily and quickly applied, thus rendering it possible to have at all times without trouble or delay a perfect point upon the pencil. It is adapted for use on ordinary lead-pencils, slate-pencils, &c. The saw-tooth and corrugated forms are especially advantageous in the sharpening of hard slate-pencils. Another important advantage of the form having several cutting edges, some cutting one way and some cutting the other, is that the pencil need have but a partial rotation back and forth in the sharpener, which makes an easier movement for the fingers. It is also free from all tendency to clog.

- Having thus described my improved pencil-sharpener and its operation, I claim—
- 20. 1. In a pencil-sharpener, a suitable holder and yielding spring-blades projecting from said holder at opposite sides thereof, said blades having longitudinally-extended slots with cutting edges tapering toward the free ends of the blades.
  - 25. 2. In a pencil-sharpener, a suitable holder, spring-blades projecting therefrom and having their free ends in yielding contact and slots in said blades extending from the point 30 of contact rearwardly toward the holder.
  - 30. 3. In a pencil-sharpener, a suitable holder and spring-blades extending out from the

end thereof, the free ends of the blades being in contact and provided with substantially elliptical slots having sharp cutting 35 edges.

4. In a pencil-sharpener, a suitable holder and spring-blades projecting therefrom, the free ends of the blades being normally in yielding contact, said blades having slots tapering outwardly and terminating at the point where contact of the blades normally begins, said slots having one or more cutting edges.

5. In a pencil-sharpener, a suitable holder adapted to receive and guide the pencil, said holder having a spring-blade projecting outwardly from the end thereof and inclined inwardly toward a line passing through the center of the holder, and a slot in the blade tapering outwardly toward the free end of the blade and terminating at a point coincident with said line passing through the center of the holder, both edges of the slot adapted to contact with the pencil during the process of 55 sharpening.

In testimony whereof I affix my signature, in presence of two witnesses, this 14th day of September, 1899.

JOHN B. MITCHELL.
